UNITED STATES PATENT OFFICE.

LIMOGE GIGUÈRE, OF MONTREAL, QUEBEC, CANADA.

CONCRETE-MOLD.

1,121,492.

Specification of Letters Patent. Patented Dec. 15, 1914.

Application filed July 14, 1913. Serial No. 779,009.

To all whom it may concern:

Be it known that I, LIMOGE GIGUÈRE, a subject of the King of Great Britain, and resident of 1886 St. Christophe Colomb street, in the city of Montreal, Province of Quebec, Canada, have invented certain new and useful Improvements in Concrete-Molds; and I do hereby declare that the following is a full, clear, and exact description of the same.

The invention is an improved concrete mold, and has for its object the provision of a machine for molding concrete blocks with great speed and facility and wherein great power can be obtained by hand for compressing the block and thus producing a better article from a point of view of durability.

The invention is an improvement on the device for which I have already made application for Letters-Patent in the United States of America, Serial No. 759,006, filed on the 5th day of April, 1913, and the present invention contains certain improvements upon the mechanism for raising and lowering the pressure plate, additional means for obtaining great pressure in squeezing the block and means for insuring that all blocks will be the same size.

The present invention also contains certain improved means for locking the sliding cover in place over the mold.

The invention is illustrated in the accompanying drawings in which—

Figure 1 is a side elevation of the machine according to the invention. Fig. 2 is a vertical section on the line A—B, Fig. 1. Fig. 3 is a side elevation of the cover locking lever and Fig. 4 is a side elevation of one of the block compressing eccentrics and adjacent parts.

Like numerals of reference indicate corresponding parts in each figure.

Referring to the drawings, 1 indicates the base of the machine formed of the pair of end frames 2 and 3, each having a central vertical guiding slot 4.

5 are bearings supported on the cross bars 6 in alinement one on each of the frames 2 and 3 toward the upper end of said frames, said bearings having the shaft 7 journaled therein and projecting a little therebeyond at each end.

8 is the mold box opening at its top and bottom as in my said previous invention and having a pressure plate 9 forming a loose

bottom to said box and adapted to be forced upwardly to squeeze the block in the mold box between itself and the sliding cover 10 which is also constructed to slide back on 60 to a bracket 11 as in my previous invention.

12 is a rod extending across the base of the machine at its lower end into the guiding slots 4, and 13 are a pair of upwardly extending lifting arms disposed within the 65 base of the machine one adjacent to each end frame and connected at their lower ends to the rod 12 and abutting the pressure plate 9 at their upper ends. The middle portion of each of the arms 13 is pierced out and 70 formed with a rack 14 on one side of said piercing which is engaged by a toothed pinion 15 loosely encircling the shaft 7, the inner side face of each of said pinions being formed with ratchet clutch teeth 16 adapted 75 to be engaged in one direction by similar shaped teeth on the clutch collars 17 which are slidably and rotatably mounted on the shaft 7 through the well known medium of key ways.

The clutch collars 17 are normally retained in contact with the teeth 16 through the medium of a coil spring 18 encircling the shaft 7 between said collars and compressing them both outwardly. It will thus 80 be seen that when the shaft 7 is turned in one direction, the collar 17 turning with the shaft, will engage the pinions 15 and rotate them also with the shaft, thus lifting the arms 13 and forcing up the pressure plate, 85 said arms being guided in their movement by the ends of the rod 12 in the slots 4. This movement however, is only utilized when forcing the finished block out of the mold, the turning of the shaft 7 being accomplished through the medium of the gear 90 95 rigidly mounted on one end of said shaft engaged by the pinion 20 to which is connected a handle 21.

It could be arranged so that the movement just described could be utilized for compressing the block within the mold, but it has been found almost impossible by such movement to make the blocks of an even depth, hence, the use of the clutch halves 16 100 and 17 which operate in conjunction with pressure arms 22 one at each end of the machine and coupled across by the bar 23 which extends through the lifting arms 13.

Within the lower end of each of the pressure arms 22 a collar 24 rotates, said collars being rigidly and eccentrically mounted on

the shaft 7 as shown in Fig. 4. It has been previously explained how the turning of the shaft 7 in one direction raises the lifting arms 13, but if the shaft is turned in the other direction it will be seen that the clutch halves 17 will slip over the teeth 16 and consequently will not turn the pinions 15. In this reverse movement however the collars 24 will obviously raise the pressure arms 22 a short distance and in doing so will force upward the lifting arms 13 as the rod 23 contacts the upper end of the piercing 14 in said lifting arms. Thus it is a reverse movement of the handle 21 which applies the compression to the block within the mold and in such compression the pressure plate 9 will be lifted a uniform distance each time so that all blocks will be the same size and compressed to the same degree. Furthermore, greater pressure can be obtained with the use of the arms 22 than could be obtained by simply forcing up the lifting arms through the medium of the pinions 15.

25 are collars loosely mounted one at each end of the shaft 7 outside of the frames 2 and 3, said collars being also eccentrically mounted on the shaft as illustrated in Fig. 3 and having the handles 26 extending forwardly therefrom.

30 27 are straps encircling the collars 25 and each having a vertically extending handle 28 passing through a slot 29 in the overhanging ends of the sliding cover 10 as in my prior invention. Each handle 28 is also 35 provided with a notch 30 adapted to engage the cover at an edge of the slot 29.

After the concrete has been placed in the mold 8 while the cover 10 is resting on the bracket 11 with the handles 28 extending 40 through the slots 29, the said handles 28 are pulled forwardly until the cover 10 is in position over the mold box as shown in Fig. 2 in which position the notches 15 engage the cover. The handles 26 are now 45 forced downwardly which has the effect of pulling down the straps 27 a short distance and consequently the handles 28 and firmly locking the cover in position on the mold box.

50 The details of the invention herein described may be somewhat modified, if found desirable, so long as I do not depart from the invention as claimed in the following claims for novelty.

55 What I claim is:

1. In a concrete mold, a frame, a mold

box supported on said frame and having a removable lid, a pressure plate loose in the opposite end of said box, an operating shaft journaled in said frame, automatic clutch means, means for raising said pressure plate a limited distance in the mold box through the rotation of said shaft in one direction and consequent upon the disengagement of said clutch means, and means for raising the pressure plate a sufficient distance to force out the finished block when the shaft is rotated in the opposite direction and consequent upon the mutual engagement of said clutch means.

2. In a concrete mold, a frame, a mold box supported on said frame, a cover for the open top of said box, a pressure plate forming a loose bottom to said box and vertically movable therein, lifting arms extending vertically below said pressure plate and adapted to lift the latter, said arms being provided with racks, means for guiding said lifting arms in their vertical movement, a shaft journaled across said frame, pinions 70 loosely mounted on said shaft and coaxing with the racks on said lifting arms and having ratchet clutch faces, clutch halves adapted to engage said faces and slidably but non-rotatably mounted on said shaft, collars rigidly and eccentrically mounted on said shaft, pressure arms encircling said collars and engaging said lifting arms and means for rotating said shaft.

3. In a concrete mold, a frame, a mold box, a sliding cover adapted to open and close the open top of said box, a pressure plate forming a loose bottom to said box, a shaft journaled across said frame, means for raising said pressure plate from the rotation of said shaft, collars loosely and eccentrically encircling said shaft one at each end and having handles extending therefrom, straps encircling said eccentrics and having upwardly extending handles passing 95 through slots in said cover and having notches near their upper ends adapted to engage the cover at the edge of said slots and lock said cover in position on said mold box when the straps are lowered by the turning 100 of said first mentioned handles.

Signed at the city of Montreal, Quebec, Canada, this 7th day of July, 1913.

LIMOGÉ GIGUÈRE.
